UNITED STATES PATENT OFFICE.

RUDOLPH M. HUNTER, OF PHILADELPHIA, PENNSYLVANIA, ASSIGNOR, BY MESNE ASSIGNMENTS, TO NORTHERN EQUIPMENT COMPANY, A CORPORATION OF DELAWARE.

BOILER FEED-REGULATOR.

1,117,388.

Specification of Letters Patent.

Patented Nov. 17, 1914.

Application filed December 28, 1908. Serial No. 469,222.

To all whom it may concern:

Be it known that I, RUDOLPH M. HUNTER, a citizen of the United States, and a resident of the city and county of Philadelphia, State 5 of Pennsylvania, have invented an Improvement in Boiler Feed-Regulators, of which the following is a specification.

My invention has reference to boiler feed regulators and consists of certain improvements which are fully set forth in the following specification and shown in the accompanying drawings which form a part thereof.

The object of my invention is to provide 15 a suitable construction of automatic water feed apparatus for steam boilers which shall be compact, simple, efficient, inexpensive, durable and quickly responsive, and moreover be adapted for use with feed water supply 20 pipes arranged high or low with respect to the normal water level in the boiler.

My invention consists of certain features of construction and combinations thereof as 25 fully described hereinafter and more particularly defined in the claims.

In general construction my improvements embody the following structures, all coöperating for controlling the supply of feed water to the boiler during its normal operation, namely; a feed water main having an automatically operated control valve formed with two check valves connected to operate in unison and constitute a differential valve which opens for discharge of water into the 35 boiler; a static device for holding the differential check valves closed upon their seats to prevent passage of water through them; an expansible element for operating the static device to remove its pressure upon the differential check valves whenever the water in the boiler reaches a point below the normal water level; a pump for pumping feed water into the boiler through the differential check valves, and a pump governor controlled by the pressure of the water upon 40 each side of the differential check valve for putting the pump into operation only when the static device for holding the differential check valves closes upon their seats.

50 My invention further comprehends many details of construction of the above elements by which they are made efficient and adjustable and especially useful in this invention.

55 My invention will be better understood by

reference to the accompanying drawings, in which—

Figure 1 is an elevation showing my invention applied to a steam boiler; Fig. 2 is a sectional elevation of the feed water control valve and operative means therefor; Fig. 3 is another elevation of the same; Fig. 4 is a detail view of a portion of the same; Fig. 5 is an elevation of the feed water control valve and its operative mechanism 6 adapted for use when the feed water pipe is low down with respect to the water level, in the boiler; Fig. 6 is a plan view of the same; Fig. 7 is a sectional view on a large scale of the adjustable end of the expansible 70 element and Fig. 8 is an elevation of one form of valve piece removed.

2 is a steam boiler of any suitable construction and is supplied with feed water from a boiler feed pump 6 by a pipe 7 provided with an automatic feed water control valve 8 and if desired with an ordinary check valve 10 and by a pipe 9 between said check valve and boiler. The control valve 8 is best shown in Fig. 2 and is of a double 80 check construction in which the two connected pieces 13 and 14 are of slightly different areas and so set respectively upon the valve seats 11 and 12 that the pressure of the water from the pump tends to lift the 85 valves to pass into the boiler when the valves are not held to their seats by external means. As the pump pressure in the pipe 7 may be ten pounds or more greater than the boiler pressure when the valves are closed, it is 90 evident that a very considerable externally applied pressure shall be employed to hold the valves closed if of a single check construction or of a balanced valve construction, and to overcome the necessity of employing such excessive externally applied pressure I construct the two valves 13 and 14 that they are of different areas, so proportioned that the excess of pump pressure may be overcome by the employment of a 100 very small externally applied pressure. This is important as the externally applied pressure has to be overcome by the normal action of a thermostatically operated mechanism. It will now be understood that, instead of it requiring an externally applied pressure equal to the area of the valve multiplied by the difference in the boiler and pump pressures, (which latter is usually not less than 10 pounds) the externally ap- 110

plied pressure may be reduced to a minimum, for example, the area of the valve multiplied by one half to one pound per square inch.

8 The valve body is provided with the bonnet 15 having an upright screw threaded neck furnished with a stuffing box 19 through which a stem 18 works and arranged to form a loose connection with the 10 valve piece. This is formed by the stem 18 being separate from the valve piece and merely abutting against it when holding it to its seat. Journaled upon the neck of the bonnet is the yoke 16, said yoke being 15 clamped in any position of adjustment about the valve body by nut 17. Hinged to the yoke at 25 is a lever 24 having a weight 26 for loading it. This lever has a connection with the stem 18 so as to raise or lower it by 20 oscillating the lever. The connection consists of a cast head 20 screwed upon the stem 18 and slotted so as to permit the lever to extend through it above the stem. Links 21 hinged at their upper ends to the head 25 20 by bolts 22 are connected at their lower ends with the lever by bolt 23. By this construction a minimum amount of friction occurs between the stem 18 and the lever.

Secured to the upper part of the yoke 16 30 is a tubular standard of iron or other metal preferably having a low coefficient of expansion, and provided on its upper end with a head 28 having socket 28^a. Between this socket 28^a and the pin 33 of the lever 24 is 35 arranged a thermostatic element 29 which is subjected to the action of steam when the water in the boiler is low and to water when the water level is normal or above. This thermostatic element is in the form of a tube 40 of copper or other highly expansible element screwed and braced into a collar 30 which is itself screwed into the socket 28^a of the head 28, said collar allowing the attachment and detachment without injury to 45 the tube.

The lower end of the expansion tube 29 is hinged to the short end of the lever 24 by the pin 33, and an intermediate head 31 having adjustable bearing 32. The head 31 50 is screwed firmly upon the lower end of the expansion tube 29 and has a lateral outlet communicating with a tube 37 connecting with boiler 2 below the water level. This head 31 has a cylindrical hole or socket 31^a in 55 its underside into which loosely fits a stud 34 secured to a bearing 32 carrying the pin 33 above mentioned and by which it is hinged to the lever 24. The stud 34 is provided with a fine pitch screw thread and upon 60 which is an adjusting nut 35 and a jam nut 37^a. The stud fits the hole 31^a in the head 31 and the adjusting nut 35 receives the thrust of the head under the action of the 65 expansion of the tube 29, and at the same time enables the parts to be nicely adjusted

in assembling the apparatus for use. The stud is in effect hinged to the lever 24 and hence the expansion tube may, under contraction, raise the head slightly from the adjusting nut and in this way prevent jamming the valve stem 18 and valve piece tight. This construction gives full freedom to the weighted lever 24 to hold the valve piece closed to its seats without the assistance of the expansion tube under contraction, said 70 tube only acting to open the valve by expansion and to allow it to close by contraction, but never holding it closed. The said result of holding the valve closed is performed by the weighted lever 24 or its equivalent, such as by the substitution of a spring 80 for the weight 26.

The expansion tube 29 is arranged obliquely to the upright 27 and its entire weight and strains are supported and sustained by the valve structure as an entirety. The short end of the lever 24 is curved upward so as to enable the connection with the expansion tube and secure a large leverage on the valve operating end. In practice I 90 prefer that the movement of the valve stem 18 shall be approximately six times the movement of the pin 33 under the action of the expansion tube, so that a relatively short expansion tube may be used and a movement of 95 secured for the stem 18 of not less than one half of an inch. When it is desired to hold the lever 24 raised, as when packing the stuffing box 19 around the valve stem 18, the lever is lifted at its weighted end and the 100 hinged locking arm 38 turned up to support it temporarily.

3 is the water column of the boiler 2 and is connected at its bottom by a pipe 5 with the boiler below the water level, and also 105 with the pipe 37 connecting with the lower head 31 of the expansion tube 29. The upper part of the water column 3 is connected with the steam space of the boiler by the pipe 4. The usual gage cocks may be arranged upon the water column. From the water column at the normal water level, there extends a pipe 36 which leads to and connects with the chamber 28^a of the head 28 at the top of the expansion tube 29 and 110 by which steam escapes into the expansion tube whenever the level of the water in the boiler falls below the normal water level and permits steam to enter the said tube. 115

The expansion tube 29 should be located 120 above the water level, as shown in Fig. 1, so that it may drain into the boiler whenever the water level of the boiler falls below the normal or main level. To secure this arrangement it is preferable to bring the feed 125 water pipe in which the valve 8 is located to about the normal water level of the boiler. In those cases where this is not possible, I provide a modified arrangement as shown in Figs. 5 and 6 and to be described later on. 130

The feed water pump 6 is supplied with steam by a pipe 39 having a pump governor 40 to control its time of operation. This pump governor comprises a balanced throttle valve 51 operated by a piston 41, working in a cylinder 50, and normally opened by the boiler pressure supplemented by a counter-weight 42. The cylinder 50 below the piston is connected by a pipe 44 with the feed water pipe 9 and the upper end of the cylinder above the piston is connected by pipe 43 with the feed water pipe 7 between the pump and valve 8. It will now be understood that if the valve 8 is closed, the pump will increase the pressure in the pipe 7 until it reaches, for example, 20 pounds above the boiler pressure and this is expended in forcing the piston 41 down against the combined action of the boiler pressure and counter-weight 42 and closes the supply of steam to the pump, thereby causing it to stop operating. The water in the boiler would, when the pump is stopped, be fully supplied and hence both pipes 36 and 37 will be water sealed and when the steam in the expansion (29) tube is condensed, said tube will also be full of water and in contracted condition, permitting the weighted lever 24, through the stem 18 to hold the valve 8 closed against the pump pressure in the pipe 7. Should the water level in the boiler become lowered so as to permit steam to enter the lower end of the pipe 36, then the said pipe, as well as the expansion tube 29, will drain and become filled with steam. This will cause the tube 29 to expand and oscillate the lever 24, removing the pressure which it had been exerting upon the valve 8. As soon as this takes place, the pressure in the pipe 7 is reduced to that of the boiler, so that the pressures above and below the pump governor piston 41 become equal and the counter-weight 42 then moves the steam valve to admit steam to the pump, whereby it starts into action and delivers water into the boiler. The pump continues to operate until, when the normal water level is reached and the pipe 36 becomes water sealed, the expansion tube 29 is made to contract and once more releases the weighted lever 24 and enables it to close the valve 8, after which, the pressure in pipe 7 increases and the pump governor once more operates to shut off steam to the pump and stop it. Where there are a plurality of boilers, they each have a valve 8 and thermostatic controlling devices, but the same pump may supply water to all of the boilers automatically and in accord with their separate demands.

In those cases where it is not convenient to have the feed water pipe at a high elevation as in Fig. 1, I provide an independent support for the thermostatic element to sustain it at a higher elevation than the water level of the boiler, and connect it by a chain

with the valve proper at a lower elevation as clearly illustrated in Fig. 5. In this construction the bracket 45 may be supported from the wall, boiler or any part of the building and the yoke 16 of the thermostatic element is clamped upon its free end by a bolt 47. Instead of being swiveled upon the neck of the valve bonnet as in Fig. 2, it is swiveled upon the neck 46 of the bracket and held in adjusted position by the washer 75 46^a and the bolt 47. By this construction the yoke may be adjusted about the neck 46 as a center and thereby throw the lever 24^a in any direction desired to coöperate with the lever 24 of the valve 8 on the feed water pipe. It will be observed that the valve in Fig. 5 is the same as in Fig. 2 except that the thermostatic features for operating the lever 24 are omitted and likewise the thermostatic element in Fig. 5 only differs from Fig. 2 in not having the valve 8 and its connections with the lever 24^a. The lever 24^a is connected with the lever 24 by a chain 48 which has an adjusting screw swivel 49 to provide the proper adjustable connection 90 between the levers 24^a and 24. The connection of the expansion element 29 with the boiler and the control of the pump is the same as in Fig. 1 and will need no further explanation. 95

As the yoke 16 of the valve 8 may be adjusted about its bonnet through 360 degrees and as the same is true of the similar yoke of the thermostatic element with respect to the neck 46 of the bracket, it is evident that these parts may always be so arranged as to enable the levers 24 and 24^a to be connected by the chain 48 to compensate for any reasonable displacement of the valve 8 to the thermostatic element with respect to a vertical line through it. 100

It is to be understood that the modification shown in Fig. 5 does not operate differently from the construction shown in Figs. 1 and 2, for in this case the lifting of the lever 24^a by the action of the expansion tube 29 lifts the lever 24 through the chain 48, the said lever 24^a and the chain 48 being a means of connection between the adjustable bearing 32 and the lever 24 from a distance 115 instead of a direct connection as in Fig. 2. 110

The operation of the apparatus, when arranged as in Fig. 5, is the same as that already described in reference to Figs. 1 and 2, only in this case the weighted lever 24 is operated by the expansion element 29 through an additional lever 24^a and the chain 48, thereby permitting the valve and thermostat to be arranged at greatly separated points of elevation. By use of the 120 features herein set out, the general construction of the apparatus may be the same for all uses and the valve and thermostat used together or in separated forms to suit the requirements of the feed water piping of 130

the boiler. The advantage is very material, not only in economy of construction, but also in facility of installation and adjustment to suit the conditions which may be present in the plant to which the regulator is to be applied.

It will be seen that my apparatus involves a construction in which the feed water control valve is of a balanced type though in its preferred form the tendency of the valve under the water pressure is to open if not otherwise prevented. The valve device is never locked against opening to pass feed water, and is combined with motive devices for directly operating it, and moreover, the said motive devices are controlled by the operation of two pipes one leading from the steam space of the boiler and the other from the boiler at the normal water level and said latter being alternately filled with water and steam, the operation being such, that when the water level in the boiler is below the normal level, both pipes are in communication with the steam space of the boiler and the motive devices operate to open the feed water control valve and when the water level in the boiler is above the normal level, one of the pipes is in communication with the steam space and the other with the water space of the boiler and the motive devices operate to close the feed water control valve. The valve is thereby positively controlled by the water level in the boiler and by the conditions existing in the two pipes leading therefrom to the motive devices for the feed water control valve. This valve is at all times responsive to the water level in the boiler and is not locked at any time against operation.

40 While for convenience of manufacture I have preferred to make the valve stem 18 separable from the valve 13-14, such independence is not at all necessary so far as the control of the valve *per se* is concerned.

45 The advantage secured by the independence lies in the fact that the stuffing box 19 may be more easily packed without disturbing the valve itself on its seat during the operation of the boiler, and in the case of filling the boiler with water before steam is generated, the valve 13-14 may be used as an unloaded check valve to avoid excessive pumping pressure.

I have shown my improvements in the form which I consider best suited to the requirements of commercial practice and while I prefer the construction shown, I do not restrict or confine myself to the details thereof as they may be modified in various ways without departing from the spirit of the invention.

Having now described my invention, what I claim as new and desire to secure by Letters Patent, is:

65 1. In a feed water regulator for steam

boilers, the combination of a valve body having a valve for controlling the feed water, a weighted lever continually tending to close the valve under constant pressure without locking the same in closed position, 70 a yoke secured to the valve body and adjustable about a vertical axis through the valve, a thermostat having its upper end fixedly supported by the yoke and having an expandable member provided with a movable 75 lower end for operating the lever against the action of the weight, a steam boiler, a water supply pipe in which the valve is located, a steam pipe connecting the lower end of the expandable member with the boiler below the water level, a pipe connecting the upper end of the expandable member with the boiler at the normal water level thereof, a pump for supplying pressure in excess of the boiler pressure to the supply pipe, and automatic 80 controlling devices to control the operation of the pump in communication with the supply pipe on opposite sides of the valve.

2. In a feed water regulator for steam boilers, the combination of a valve body having a valve for controlling the feed water, a weighted lever for closing the valve, a yoke secured to the valve body, and a thermostat supported by the yoke consisting of a standard and an expandable member 90 connecting at its top with the standard and at its bottom with the lever for operating the lever against the action of the weight, a steam boiler, a steam pipe connecting the lower end of the expandable member with the boiler below the water level, a pipe connecting the upper end of the expandable member with the boiler at the normal water level thereof, a pump for forcing water into the boiler through the valve, and an automatic 95 device for putting the pump into and out of operation controlled by the pressures upon opposite sides of the valve.

3. In a feed water regulator, the combination of a boiler and feed water pipe, a valve body on said feed water pipe and having two seats therein of different areas and having a chamber between the seats and a second chamber in communication with opposite sides of the seats, a double check valve having two valve pieces of different areas adapted to respectively seat upon the two valve seats and in which the valve piece of largest area opens against the boiler pressure, means to close the valve pieces upon their seats consisting of a weighted lever, a yoke secured to the valve body and supporting the lever, a standard supported by the yoke, an expansion tube connected at one end to the standard and at the other end to the lever, adjusting devices for adjusting the extent of action of the expansion tube upon the lever, means controlled by the level of the water in the boiler for supplying steam or water to the expansion tube, and 100 105 110 115 120 125 130

a supply pipe delivering water to the valve body between the valve seats at a pressure in excess of the boiler pressure.

4. In a feed water regulator, a valve body and valve piece, a yoke carried by the valve body, a weighted lever pivoted to the yoke for operating the valve piece, a standard supported by the yoke, a thermostatic element connected at one end with the standard and at the other end with the lever, and means for adjusting the extent of action of the thermostatic element upon the lever consisting of a head 32 hinged to the lever and having a screw threaded stud 34 sliding in the end of the thermostatic element, and an adjusting abutment nut 35 against which the thermostatic element presses when operating the lever.

5. In a feed water regulator, a valve body and valve piece, a stem for operating the valve, a pivoted weighted lever for depressing the stem, a thermostatic device supported by the valve body and having its free end pressing downward upon the weighted lever to operate it, and connecting means for simultaneously adjusting the lever and thermostatic device axially about the stem and valve body and maintaining their relative positions with respect to each other and the valve stem.

6. In a feed water regulator, a boiler, combined with a valve body, a loose check valve piece therefor, a bonnet for the body and having a neck and stuffing box, a valve

operating stem extending through the stuffing box and independent of the valve piece, a yoke adjustably clamped upon the neck of the bonnet so as to be rotated about the stem as a center, a weighted lever hinged to the yoke and actuating the stem, means controlled by the water level of the boiler and supported by the yoke for operating the lever and means for forcing water through the check valve against the boiler pressure controlled by the difference in pressures on opposite sides of the valve.

7. In a feed water regulator, a valve body, a valve piece therein, a valve stem to operate the valve, a weighted lever supported by the valve body for operating the valve stem to close the valve piece upon its seat, a thermostatic device arranged about the valve body having its free end pressing upon the lever for permitting the valve to open, and connecting means between the thermostatic device and weighted lever to which they are attached said means being adjustably clamped upon the valve body so as to be rotatable axially to the valve stem while maintaining the relative positions of the lever and thermostatic device with respect to each other and to the valve stem.

In testimony of which invention, I hereunto set my hand.
